CASTER BRACKET

Edward H. Schultz, Jr., Chicago, Ill., assignor to The Nagel-Chase Manufacturing Company, Chicago, Ill., a corporation of Illinois

Application June 5, 1953, Serial No. 359,769

5 Claims. (Cl. 16—29)

The present invention relates to a novel structure for supporting various articles, and more particularly to a novel structure for supporting articles of furniture and the like for easy movement.

There are many instances when it is desirable to support articles of furniture on casters or the like for easy movement across the floor. For example, television sets are often moved or twisted to present them to a particular part of a room for better viewing. It is particularly desirable in moving television sets and the like that the article be supported so that it may be moved without substantial jarring and toward this end casters having relatively large diameter wheels are provided. Such large diameter wheels are, however, rather unsightly if mounted to the bottom edge of the article of furniture, and, therefore, it is desirable that the casters be mounted by brackets within the article so that only portions of the wheels extend below the bottom of the article of furniture. In many instances, the article of furniture, such as a television set, is not adapted to receive such caster mounting brackets, and, therefore, a separate base or dolly is provided. In the past, brackets of this general nature have been mounted on the article of furniture or the dolly by means of screws and the like, but this method is often relatively time consuming and difficult under cramped conditions, and, therefore, costly. It is an object of this invention to provide a novel supporting structure of the above described general type which is of simple and economical construction and which may be easily assembled without auxiliary fastening means, such as screws.

A more specific object of the present invention is to provide a novel caster mounting bracket of the above described type which may be quickly and easily connected with the article to be supported without auxiliary fastening means, such as screws and the like.

Another object of this invention is to provide a novel caster bracket of the above described type which may be quickly and easily made from sheet material stock and which is relatively strong and rigid.

Other objects and advantages of the present invention will become apparent from the following description and the accompanying drawings, wherein:

Fig. 1 is a perspective view, showing a base or dolly embodying the features of this invention;

Fig. 2 is an exploded perspective view, showing a novel caster assembly embodying the features of this invention;

Fig. 3 is an enlarged fragmentary cross sectional view taken along line 3—3 in Fig. 1;

Fig. 4 is a fragmentary cross sectional view taken along line 4—4 in Fig. 3;

Fig. 5 is a fragmentary cross sectional view taken along line 5—5 in Fig. 3; and

Fig. 6 is a fragmentary perspective view illustrating a portion of the novel caster bracket of this invention.

Referring now more specifically to the drawings, wherein like parts are designated by the same numerals throughout the various figures, a dolly embodying the

2

novel features of this invention is generally designated by the numeral 10. In the illustrated embodiment, the dolly 10 includes four sides 12, 14, 16, and 18 which are joined together at their ends by any suitable means, such as nails, screws, or glue. Preferably, a top member 20 extends between and is connected to opposite sides of the dolly for adding rigidity to the structure. In the event the dolly is to be used to support an article of furniture, such as a television set 21, shown in dotted lines in Fig. 1, the member 20 is designed to fit within suitable recesses in such article of furniture to retain the article on the dolly. Each of the corners of the dolly is also reinforced by a block-like member 22, which is rigidly secured to adjacent sides of the dolly by any suitable means, such as nails, screws, or glue. In the illustrated embodiment, these blocks 22 are rectangular in shape and recessed, as at 24 and 26, in order to receive a caster mounting bracket in the manner described hereinbelow.

In accordance with the present invention, a novel bracket 28 is provided for mounting a caster to the dolly. The caster may be of any usual design and includes a relatively large diameter wheel 30 rotatably mounted on a bifurcated member 32 by a pin 34. A stem 36 is secured to and extends from the bifurcated member for insertion into a suitable socket on the bracket 28. Preferably, the stem is frictionally retained within the socket by means of a resilient split ring 38 mounted partially within a suitable annular recess in the stem.

The caster mounting bracket 28 is preferably formed from sheet material, such as sheet metal. The bracket includes a socket portion 42 which may be made by suitably doubling over and forming an intermediate portion of a sheet material blank. The socket is greatly strengthened by short sections 44 and 46 which extend laterally from abutting edges of the socket portion. Preferably, the sections 44 and 46 are secured together by means of a plurality of spot welds 47. In order to space the caster wheel from the sides of the dolly, arms 48 and 50 extend from the sections 44 and 46, respectively, to a bracket mounting end portion. Preferably, the arms 48 and 50 are arranged in diverging relationship to give the brackets strength and rigidity. The mounting end portion of the bracket includes sections 52 and 54 which extend respectively from the arm portions 48 and 50. The sections 52 and 54 are preferably disposed at substantially right angles to each other and are adapted to overlie and conform to surfaces 56 and 58 of the member 22. The sections 52 and 54 are secured as by spot welds 55 to opposite sides 60 and 62 of a V-shaped metal insert. The sides 60 and 62 of the metal insert terminate in inturned flanges 64 and 66. These flanges are adapted to slide into the recesses 24 and 26 in the member 22 for engagement with surfaces 68 and 70, whereby opposed surfaces on the bracket provided by the sides 60 and 62 and the flanges 64 and 66 cooperate with opposed surfaces on the member 22 for securely connecting the bracket to the member 22, and hence the dolly. Preferably, the recesses 24 and 26 open at the bottom of the member 22 so that in order to connect the bracket, it is merely necessary to slide the flanges 64 and 66 upwardly into the recesses. In order to limit such upward sliding movement, the lower edges of the bracket sections 52 and 54 terminate in inturned flanges 72 and 74 which are adapted to engage the bottom surface of the member 22. In some instances, the metal V-shaped insert may be eliminated, and the flanges 64, 66, 72, and 74 may be formed integral with the sections 52 and 54 of the bracket. However, it is usually preferable to use the V-shaped insert since this structure adds considerable strength and rigidity to the bracket.

From the above description, it is seen that the present

invention has provided a novel structure, wherein the caster mounting bracket may be quickly and easily assembled with and secured to the article to be supported without the use of auxiliary fastening means, such as screws, bolts, or the like. In addition, it is seen that the novel caster mounting bracket of this invention is of simple construction and may be economically manufactured from sheet material stock and has considerable strength and rigidity.

While the preferred embodiment of the present invention has been shown and described herein, it is obvious that the novel caster mounting bracket may be secured to various articles in addition to the described dolly and that various structural details may be changed without departing from the spirit and scope of the 10 appended claims.

This invention is claimed as follows:

1. A bracket of the type described, comprising socket means adapted to receive a caster pintle or the like, an attachment portion connected with said socket means, 20 said attachment portion including a pair of sections extending away from each other for substantially traversing angularly disposed surfaces of a structure to be supported, an insert disposed between said sections and having sides secured to each of said sections, flange means extending from each side of said insert and adapted to slide upwardly along and interengage with other surfaces on a structure to be supported and angularly disposed with respect to said first mentioned surfaces, and additional flange means extending from said attachment portion and engageable with said structure for limiting upward movement of the bracket relative to said structure, whereby said flange means securely mount the bracket on said structure.

2. A bracket of the type described, comprising socket means adapted to receive a caster pintle and the like, an attachment portion connected with said socket means, said attachment portion including a pair of angularly disposed sections extending away from each other, a generally V-shaped insert disposed between said sections and having sides secured to each of said sections, said insert having generally vertically disposed free edge portions terminating in inturned flange means, and said attachment portion having generally horizontally disposed flange means extending from lower marginal portions thereof.

3. A bracket of the type described, comprising an elongated generally vertically disposed sheet material socket portion adapted to receive a caster pintle, a pair of arm sections integral with and extending laterally from said socket, outer end portions of said arm sections being disposed in diverging relationship, an attachment portion connected with said outer end portions of said arm sections, said attachment portion including a pair of angularly disposed sections, vertically disposed inwardly directed flange means extending from adjacent free ends of each of said last mentioned sections, and generally horizontally disposed flange means extending from adjacent a lower margin of at least one of said last mentioned sections.

4. A bracket, as defined in claim 3, wherein said attachment portion includes a generally V-shaped insert disposed between and secured to said attachment portion sections, and at least some of said flange means are integral with said insert.

5. A device of the type described, comprising a structure to be supported, which structure includes a pair of angularly disposed members joined together and providing a corner, a block disposed within said corner and secured to said members said block having vertically extending recesses in sides thereof disposed against said members, which recesses provide slot means between each of said members and said block, a bracket including a pair of diverging sections overlying said block, each of said sections terminating in flange means removably insertable into one of said slot means for connecting the bracket to said block, additional flange means extending from lower edges of said sections and projecting beneath said block to limit upward movement of said bracket relative to said block, and socket means integrally interconnected with and disposed laterally of adjacent edges of said sections, and support means carried by said socket means.
